(57) **CLAIM**

The ornamental design for an electronic lock, as shown and described.

DESCRIPTION

FIG. 1 is a perspective view of an electronic lock, showing the new design;

FIG. 2 is a top view of the electronic lock;

FIG. 3 is a front view of the electronic lock;

FIG. 4 is a right side view of the electronic lock;

FIG. 5 is a bottom view of the electronic lock;

FIG. 6 is a left side view of the electronic lock; and

FIG. 7 is a rear view of the electronic lock.

FIG. 8 is a perspective view of an electronic lock showing a second embodiment of the new design;

FIG. 9 is a top view of the electronic lock of FIG. 8;

FIG. 10 is a front view of the electronic lock of FIG. 8;

FIG. 11 is a right side view of the electronic lock of FIG. 8;

FIG. 12 is a bottom view of the electronic lock of FIG. 8;

FIG. 13 is a left side view of the electronic lock of FIG. 8;

FIG. 14 is a rear view of the electronic lock of FIG. 8;

FIG. 15 is a perspective view of an electronic lock showing a third embodiment of the new design;

FIG. 16 is a top view of the electronic lock of FIG. 15;

FIG. 17 is a front view of the electronic lock of FIG. 15;

FIG. 18 is a right side of the electronic lock of FIG. 15;

FIG. 19 is a bottom view of the electronic lock of FIG. 15;

FIG. 20 is a left side view of the electronic lock of FIG. 15;

FIG. 21 is a rear view of the electronic lock of FIG. 15;

FIG. 22 is a perspective view of an electronic lock showing a fourth embodiment of the new design;

FIG. 23 is a top view of the electronic lock of FIG. 22;

FIG. 24 is a front view of the electronic lock of FIG. 22;

FIG. 25 is a right side view of the electronic lock of FIG. 22;

FIG. 26 is a bottom view of the electronic lock of FIG. 22;

FIG. 27 is a left side view of the electronic lock of FIG. 22;

and,

FIG. 28 is a rear view of the electronic lock of FIG. 22.

(Continued)

The broken lines are shown for the purpose of illustrating parts of the electronic lock that form no part of the claimed design.
